STRINGED MUSICAL INSTRUMENT

Elmer F. Stromberg, Cambridge, Mass.

Application May 31, 1946, Serial No. 673,242

4 Claims.

(Cl. 84—293)

1

My present invention relates to stringed musical instruments and particularly to adjustable means built into the neck structure for such instruments to apply corrective stresses substantially at and towards opposite ends of the neck thereby to straighten the neck should it become bowed by string tension.

The bowing of the necks of stringed instruments is a common occurrence and is obviously objectionable in that it makes it impossible to play the instrument accurately. This result is due to the fact that as the strings are depressed by the fingers of the player against the bowed finger board, the tautness of the strings varies appreciably as compared to an unbowed neck in which the strings and the finger board are in parallel.

In accordance with my invention, I provide a neck structure having a longitudinal channel extending from adjacent its body attaching end forwardly into the head which is angularly disposed with respect to the neck and which is provided with rotatable pegs by which the strings are tensioned. Extensible means in the channel are operative to apply a corrective stress substantially at and towards the opposite ends of the neck.

My extensible means includes a rotatable member and preferably the rotatable member is located in the neck closely adjacent the junction of the head and the neck. The finger board has an opening permitting access to the rotatable member, but otherwise it conceals the channel and the extensible means. In accordance with my invention, the finger board opening is established by terminating it short of the finishing layer on the head thereby to establish a slot to receive the string nut or support which constitutes a closure for the opening and which is tightly held in place when the instrument is strung.

Preferably, my extensible means comprises a rod having one end downturned so that it may be easily anchored in the channel adjacent its body attaching end. The other end of the rod is threaded and extends into the head and is slightly downturned as required by the angular relation between the neck and the head. I mount a member in the channel which establishes a transverse shoulder adjacent the junction of the head and the neck through which the threaded end of the rod freely extends. Threaded on the rod on the neck side of the shoulder and in engagement with the shoulder is a nut which, when rotated, causes stress to be exerted adja-

2

cent to and towards the opposite ends of the neck thereby to correct any bowing of the neck due to string tension.

In the accompanying drawings, I have shown 5 an illustrative embodiment of my invention from which its several novel features and advantages will be readily apparent.

In the drawings:

Fig. 1 is a fragmentary and partly broken away 10 view of an instrument of the guitar type in accordance with my invention.

Fig. 2 is a section along the lines 2—2 of Fig. 1, and

Fig. 3 is a section along the lines 3—3 of Fig. 2 15 on an enlarged scale with a part of the string nut broken away.

In the drawings, I have indicated generally at 5 the neck structure of a stringed musical instrument in accordance with my invention. The neck structure 5 includes a neck 6, one end 7 of which is conventionally formed and attached to the neck block 8 of the body 9 of the instrument. The other end of the neck 6 is formed to establish a head 10 disposed at an angle to the neck 6.

The neck 6 has on its upper surface a finger board 11 and the head 10 is finished as by the layer 12. Each of the strings 13 is attached at one end to the body 9 of the instrument and is supported in spaced relation to the finger board 11 and to the other strings by a string nut or support 14. The other end of each string 13 is connected to the part of a rotatable key 15 by which it may be suitably tensioned or released.

Because of the angular relation between the 35 head 10 and the neck 6, and because of the tension on the strings, the neck 6 is apt to become bowed and the usefulness of the instrument seriously impaired.

Such bowing of the neck may be overcome, 40 in accordance with my invention, by providing the upper surfaces of the neck structure with a channel 16 extending adjacent the neck end 7 forwardly into the head 10. Adjacent the junction between the neck 6 and head 10, I widen the channel 16 to establish a nut accommodating chamber 17.

I anchor a member 18 in the channel 16. 45 This may be easily effected by forming the member 18 with a downturned end 19 which may be suitably anchored by driving it into the neck end 7. The other end of the member 18 is threaded as at 20 and extends into the head 10. Because 50 of the angular relation between the neck 6 and the head 10, the member 18 is preferably bent

so that the threaded end 20 extends slightly downwardly.

I thread a nut 21 on the end 20 and in the head 10 I have shown a transversely disposed member 22 anchored to the head 10 as by screws 23 and establishing a shoulder 24 substantially at the junction of the neck 6 and the head 10. The threaded end 20 of the member 18 passes freely through the shoulder 24 which is disposed between the nut 21 and the head 10. By this structure, by rotating the nut 21 to advance it towards the head 10, corrective stress is applied at opposite ends of the neck 6 and towards those ends so that any bowing of the neck 6 may be corrected.

In practice, I prefer to provide the neck 6, adjacent its head end, with a channel straddling guard 25, anchored to the neck 6 as at 26 to eliminate any possibility of the member 18 itself bowing as the nut 21 is rotated, and engaging the finger board 11 and tending to separate it from the neck 6.

In practice, I provide a slot-shaped opening 27 in communication with the chamber 17 by terminating the finger board 11 short of the layer 12 on the head 10. This opening is normally closed by the string nut or support 14 which is held tightly seated therein when the instrument is strung. When the instrument is unstrung, the string nut 14 may be removed to permit the nut 21 to be rotated by means of a wrench, not shown.

As will be apparent from the drawings, the neck 6 tapers towards the head 10 and is, accordingly, more likely to bow adjacent the head. For that reason, I form the chamber 17 so that only at its front end, that is, under the opening 27, is it sufficiently larger than the nut 21 to accommodate the wrench. By this construction, I am able to utilize means for providing a corrective stress at the head end of the neck 6 without removing sufficient wood to appreciably weaken the neck in its zone in which bowing is most likely to occur.

Neck structures for stringed musical instruments in accordance with my invention are well adapted to correct the bowing of the neck. Not only are the corrective stresses applied at the extremities of that part of the neck in which bowing occurs, but also adjustments may be easily made. At the same time, the mechanism is wholly concealed so that the appearance of the instrument is not interfered with and the mechanism itself is inexpensive to manufacture and is easily installed.

What I therefore claim and desire to secure by Letters Patent is:

1. A neck structure for a stringed musical instrument, said structure comprising a neck, one end of which is attached to one end of the body of the instrument to the opposite end of which body the strings are connected, and an angularly disposed head on the other end of said neck for the rotatable pegs to which the strings are connected and by which they are tensioned, said structure having a longitudinal channel in its

upper surface extending from adjacent the body attaching end of said neck into said head, a thrust member transversely anchored in said channel adjacent the junction of said neck and head a finger board closing said channel and terminating short of said head to provide a slot-shaped opening in communication with said channel adjacent said thrust member, a transverse string support positioned in said opening to establish a closure therefor, said support being held in place by the strings when the instrument is strung, extendable means anchored to said neck in said channel adjacent its body attaching end and in said head, said means including a rotatable member bearing against said thrust member and accessible through said opening when said support is removed so that should said neck become bowed by string tension a corrective stress may be applied substantially at and towards its opposite ends by rotating said member to extend said means.

2. A neck structure for a stringed musical instrument, said structure comprising a neck, one end of which is attached to one end of the body of the instrument to the opposite end of which body the strings are connected, and an angularly disposed head on the other end of said neck for the rotatable pegs to which the strings are connected and by which they are tensioned, said structure having a longitudinal channel in its upper surface extending from adjacent the body attaching end of said neck into said head and being widened to establish a chamber in adjacent portions of said neck and head, a member anchored in said channel adjacent its body attaching end and extending into said head, the chamber entering end of said member being threaded, means anchored to the upper surface of said head on opposite sides of said channel and including a flange depending into said chamber to provide a transverse shoulder substantially at the junction of said head and neck and being apertured freely to receive said member, and a nut threaded on said member and disposed between its anchored end and said shoulder so that should said neck become bowed by string tension a corrective stress may be applied substantially at and towards its opposite ends by advancing said nut against said shoulder.

3. The neck structure of claim 2 and a transversely disposed retaining member spanning the channel adjacent the head end of the neck and connected directly thereto.

4. The neck structure of claim 2 in which the member is a rod having a downturned end anchored in the neck and having its threaded end disposed downwardly at an angle to its intermediate position.
